UNITED STATES PATENT OFFICE.

JOHN G. NEFF AND CHARLES A. NEFF, OF DAVEY, NEBRASKA.

RINGER AND SECRET-SERVICE DEVICE.

1,108,847. Specification of Letters Patent. Patented Aug. 25, 1914.

Application filed June 2, 1909. Serial No. 499,644.

To all whom it may concern:

Be it known that we, JOHN G. NEFF and CHARLES A. NEFF, citizens of the United States, residing at Davey, in the county of Lancaster, State of Nebraska, have invented certain new and useful Improvements in Ringer and Secret-Service Devices; and we do hereby declare the following to be a full, clear, and exact description of the invention, such as will enable others skilled in the art to which it appertains to make and use the same.

This invention relates to telephone apparatus and has special reference to what is preferably termed a ringer and secret service device for use on party line telephones.

One object of the invention is to provide a novel device which shall insure the alarming of but one of the telephones in a party line system.

Another object of the invention is to provide a novel mechanism so that only the proper party, or party called, will be able to open the speaking and listening circuit of a party line telephone system.

A third object of the invention is to provide an apparatus of the kind described which may be used in connection with the ordinary form of telephone.

A fourth object of the invention is to provide a novel form of apparatus in which all the other parties on the telephone system will be warned of the use of one of the telephones and be notified of what telephone is in use so that they will not answer their own telephone when the desired telephone is called but only the proper party will answer the telephone.

With the above and other objects in view, the invention consists in general of a step by step mechanism electrically actuated from the switchboard of a telephone system and arranged on a party line, there being a mechanism for each of the telephones on a party line and the mechanisms being arranged to successively place the various telephones of the circuit in operative relation to the main line.

The invention further consists of certain novel details of construction and combinations of parts, hereinafter fully described, illustrated in the accompanying drawings, and specifically set forth in the claims.

In the accompanying drawings, like characters of reference indicate like parts in the several views, and; Figure 1 is a diagram-

matic view partly in elevation showing the general arrangement of wiring of a system as used in connection with this invention. Fig. 2 is a front elevation of a phone equipped with this system, the front being removed to show the working parts. Fig. 3 is a detailed side elevation partly in section of a portion of the step by step mechanism, the section being taken on the line 3-3 of Fig. 2. Fig. 4 is a detailed section taken on the line 4-4 of Fig. 3. Fig. 5 is a similar detail taken on the line 5-5 of Fig. 3. Fig. 6 is a view of the indicator dial used on the outside of the device; together with the pointer. Fig. 7 is a diagrammatic view of a telephone circuit constructed in accordance with our invention.

It is to be understood that in Fig. 1, the diagram there shown is merely indicative of one form of wiring adapted to be used in connection with this invention. Inasmuch as there are various forms of wiring used with the ordinary telephone, and this invention is capable of being used in connection with any one of these forms, only that portion of the diagram relating to this invention will be described.

The apparatus used for accomplishing the purpose of this invention is as follows: The numeral 10 indicates the casing of an ordinary telephone. This telephone is here shown as equipped with the usual transmitter 12, receiver 11 and magneto bell 13. Above the casing 10 is a back board 14 and upon this back board is mounted a frame 15 whereon is supported a pair of magnets 16. Pivotally mounted as at 17 is an armature 18 provided with an extended arm 19. Upon the frame 15 is mounted a bracket 20 wherein is supported a shaft 21. Supported on the outer end of the arm 19 is a pawl 23 provided with a flat portion 24. Attached to a bracket 25 secured to the frame 15 is a spring 26, the free end of which bears against the flat portion 24 of the pawl 23. The pawl 23 has two arms, one of which is always in engagement with one of the teeth of the ratchet 22 so that said ratchet is positively locked at all times. It will be thus observed that when the armature 18 is attracted by the magnets 16, the pawl 23 will be lifted as a whole from engagement with the teeth of the ratchet 22 and that when the magnets are deenergized, the spring 26 will cause the pawl to be returned to engagement with the teeth of said ratchet, and

in so doing one of the arms will engage the tooth above the one which it had previously left, and thereby rotate said ratchet one step. At the same time the other arm of the pawl 5 will engage a tooth and form a stop to limit such step by step movement.

A sleeve 27 is secured to the shaft 21 and upon this sleeve is provided a collar 28. Fixedly mounted on the sleeve 27 is a plate 29 provided with a fixed pin 30. Slidably and rotatably mounted on the sleeve 27 is a plate 31 provided with a fixed pin 32. A spring 33 is provided between the plate 31 and the collar 28 so that the plate 31 is normally pressed in the direction of the plate 29. The plate 29 is provided with a series of perforations 34 any one of which is adapted to receive the pin 32 according as the plate 31 is pushed in and revolved so that the pin 32 comes opposite one of the perforations of the plate 29. By this means the pin 32 may be set any number of steps from the pin 30, the number of perforations 34 being equal in number to the teeth on the ratchet 22. Upon the shaft 21 is also mounted a plate 35 having a fixed pin 36 secured thereto.

Upon the bracket 20 is formed an arm 37 and between the bracket and this arm is supported a shaft 38. To the shaft 38 is secured a bent lever 39, one arm of which is upwardly curved as at 40 and is adapted to contact with the pins 30 and 32 as the shaft 21 is rotated. The other arm of the lever 39 is re-bent as indicated at 41 and is provided on the re-bent end with an insulated block or head 42. Upon the receiver fork 43 is mounted a plunger 44 which extends up and is adapted to strike the block 42 whenever the same is in position thereto. The parts 42 and 44 are normally kept out of coöperative relation by means of a spring 45, one end of which is secured to the arm 40 and the other end to the frame 20. Upon the frame 20 is also mounted a resilient pawl 46 adapted to engage the ratchet 22 and prevent the same from being turned backward.

At 47 is a resilient contact finger and at 48 another finger adapted to coact therewith upon contact with the pin 36 with the first mentioned finger.

At 49 is another resilient contact finger and at 50 still another, a third finger 51 being positioned between the last two fingers for purposes that will hereinafter be described. These last three contact fingers are so arranged that when the arm 40 of the lever 39 is struck by one of the pins 30 or 32, the block or head 42 will lie beneath the contact fingers at the free ends thereof. From the contact finger 51 a wire 52 leads to a ground 53. Connecting the ground wire 52 with the fork 43 is a wire 54. Extending from a contact 55 adapted

to be struck by the fork 43 is a line wire 56. Extending from a similar contact 57 to the receiver 11 is a wire 58. Extending from the receiver 11 to the resilient finger 49 is a wire 59 and extending from the resilient 70 finger 50 is a line wire 60.

At 61 is indicated a transformer connecting the receiver and transmitter circuits and the line circuits. In the transmitter circuit, which includes the ordinary battery 62, the current goes through the transmitter 12, through the wire 62', to the primary coil 61' of the transformer and from thence through the batteries to the wire 56 and from thence through the contact 55 to the wire 63' through which it passes back to the transmitter. The impulses formed in this circuit are transmitted to the receiver 11 and to the line circuit by a circuit which extends from the receiver 85 through the wire 58, through the contacts 57 and 55 to the wire 56, from thence through the secondary coil 61'' of the transformer and from thence through the wire 60, and the contact pins 49, 50 and 51 90 to the wire 59, through which it passes back to the receiver.

At 62' is indicated a wire leading from the transmitter to the line wire 56 and at 63 is the ground wire of the transmitter. A 95 wire 64 extends from one end of the magnet winding 16 to the magnet of the magneto bell 13 and a wire 65 extends from the other end of the winding of the magnet 16 to the finger 48.

At 66 is indicated a pair of resilient contact fingers which are located on the switchboard of the central station.

At 67 is the usual ringing jack provided with a contact finger 68 and receiving its 105 current from a battery or the like as indicated at 69. Extending from one of the contact fingers 66 is a wire 70 leading to the wire 64 and from the other contact finger a wire 71 leads to the wire 65.

The end of the shaft 21 extends through the casing and is provided with dial 72 fixed on said shaft having a series of numbers 73 arranged therearound equal in number to the number of notches on the ratchet 22. A 115 pointer 73' is fixedly mounted on the casing above dial 71.

Before any of the telephones have been rung the parts are in the position indicated in Fig. 1, that is to say the pin 30 is in 120 contact with the arm 40, the plug 42 lies underneath the free ends of the fingers 49, 50 and 51 and the pin 36 has closed the contact between the fingers 47 and 48. Under these circumstances, if a person desires to 125 call the central station, he removes the receiver from the fork and the fork 43 will rise. This will carry with it the plunger 44 and close the circuit through the fingers 49, 50 and 51, thus permitting the central sta- 130

tion to be called in the usual manner. Now let it be supposed that some other telephone is rung and it is desired to call a certain station on a party line equipped with this device. In the present instance the pin 32 is indicated as being immediately adjacent the pin 30, which is the position in which the pin 32 would be placed for the first station or number 1. The central operator receiving the call inserts the jack 67 between the fingers 66 and presses upon the button 68. This moves the various plugs 42 out from beneath the ends of the fingers 49, 50, and 51, but the plug 42 at station number 1 is immediately moved back by the action of the pin 32. At the same time the pin 36 closes the circuit through the fingers 48 and 47. This will close a circuit from the battery 69 through one side of the jack 67, one of the fingers 66, wire 70, wire 64, magneto 13, a wire 74 connecting the magneto with the finger 47, finger 48, a wire 75 connecting the finger 48 with the wire 71, and back through the wire 71 to the other one of the fingers 66, jack 67 and battery 69. This will cause the magneto bell 13 to be rung and the bell will continue ringing as long as the finger 68 is depressed. It will be apparent that the movement of the ratchet 22 is accomplished by the depression of the armature 18 as is usual in electrical step by step movements. Now when the person called hears his bell ring in this manner, he answers by removing the receiver 11 from the fork 43. This permits the plunger 44 to rise in the manner previously described and closes the circuit through the fingers 49, 50 and 51. If, however, any other person removes their receiver and attempts to listen to the conversation, the fingers 49, 50 and 51 will not be brought into contact for the reason that the plug 42 will be out of alignment with the ends of the fingers and the plunger 44 so that the removing of the receiver from the fork will fail to establish the circuit desired.

It is obvious that the pins 36 and 32 must be so positioned that the telephone corresponding to the number of steps which the pin 32 is removed from the pin 30 will be rung. It will also be obvious that as each telephone is rung the same will be indicated on the dial 72 and that as the various pins 36 move past the fingers 47 and 48 they will momentarily close the circuit and ring the magneto bell 13 one or two strokes. By means of this dial it will be obvious to any person approaching the telephone when another telephone on the same party line is in use that the system is being used so that they will not attempt to call central until the dial has been replaced to the zero point by means of successive depressions of the contact 68 previously described. When the ringing jack 67 closes the circuit, current will then

flow through wire 70, magnet 16, wire 65 and thence back through wire 71 to the jack. Simultaneously a parallel circuit will be closed through wires 64, bell 13, wire 74, through contact fingers 47 and 48, through wire 75, and thence through wire 71 back to the jack. There has thus been provided a simple and efficient device of the kind described and for the purpose specified.

It is obvious that many minor changes may be made in the form and construction of this invention without departing from the material principles thereof. It is not, therefore, desired to confine the invention to the exact form herein shown and described, but it is wished to include all such as properly come within the scope of the appended claims.

Having thus described the invention, what is claimed as new, is:—

1. In a device of the kind described, a series of telephones, a step by step mechanism for each of said telephones, a common normally open circuit for all of said step by step mechanisms, a central station, means at said central station to close all of said step by step mechanisms, means actuated by the several step by step mechanisms to close the signal circuit successively at the several telephones, talking circuit closing elements at each of said telephones, and means at each of said telephones operable by said step by step mechanisms to successively place said circuit closing elements in operative position.

2. In a device of the kind described, a series of telephones, a transmitter fork at each of said telephones, a step by step mechanism for each of said telephones, a common normally open circuit for all of said mechanisms, a central station, means at said central station to close the circuit through all of said step by step mechanisms, means actuated by the several step by step mechanisms to close the signal circuit successively at the several telephones, a talking circuit closing element supported on said receiver fork, a second talking circuit closing element movable into and out of operative relation to the first element at each of said telephones, and means at each of said telephones operable by said step by step mechanisms to successively place the second element in operative relation to the first and permit the closing of said talking circuit successively at the several telephones.

3. In a device of the kind described, a series of telephones each provided with a receiver fork, a step by step mechanism for each of said telephones, a common normally open circuit for all of said step by step mechanisms, a central station, means at said central station to simultaneously close the circuit through all of said step by step mechanisms, a shaft rotated by said step by step

mechanisms, a disk on said shaft, a pin projecting from said disk, a circuit closer in the path of and operable by each of said pins, said circuit closers forming a part of said 5 signal circuit, said pins being displaced in step by step relation around the several disks to successively close the signal circuit at the successive telephones, a talking circuit closing element carried by each of said receiver forks, a second talking circuit closing element at each of said telephones movable into operative relation to the first mentioned talking circuit closing element and means at each of said telephones operable by said 10 step by step mechanisms to successively place the second talking circuit elements in operative position with relation to the first talking circuit closing elements.

4. In a device of the kind described, a series of telephones each provided with a receiver fork, a step by step mechanism for each of said telephones, a common normally open circuit for all of said step by step mechanisms, a central station, means at said 15 central station to simultaneously close all of said step by step mechanisms, a shaft rotated by said step by step mechanisms, a disk on said shaft, a pin projecting from said disk, a circuit closer in the path of and operable by each of said pins, said circuit closers forming a part of said signal circuit, said pins being displaced in step by step relation around the several disks to successively close the signal circuit at the successive 20 telephones, a talking circuit closing element carried by each of said receiver forks, a second talking circuit closing element at each of said telephones movable into operative relation to the first mentioned talking circuit closing element, a second disk carried by and rotating with said shaft, a pin on said second disk normally holding the second element in operative relation to the first element, a second pin carried by said second 25 disk, each of said second pins being in stepped relation successively throughout the several telephones, and means supporting the second circuit closing element at each of

said telephones adapted to move the same into operative relation with the first circuit closing element, said means being arranged to be simultaneously freed from all of the first mentioned pins and successively struck by the second mentioned pins of the successive telephones. 55

5. In a device of the kind described, an electrically actuated step by step mechanism, a shaft rotated thereby, a disk rigidly mounted on said shaft provided with a series of openings concentrically arranged therearound, a circuit closing element, means for supporting the same, a pin projecting from said disk normally in contact with said means, a second disk slidably and rotatably held upon said shaft, a pin fixed on said second disk adapted to be projected through one of said openings, and a spring normally forcing the second disk toward the first. 60

6. In a device of the kind described, an electrically actuated step by step mechanism, 70 a shaft rotated thereby, a disk rigidly mounted on said shaft provided with a series of openings concentrically arranged therearound, a circuit closing element, means for supporting the same, a pin projecting from said disk normally in contact with said means, a second disk slidably and rotatably held upon said shaft, a pin fixed on said second disk adapted to be projected through one of said openings, a spring normally 75 forcing the second disk toward the first, a third disk rigidly mounted on said shaft to rotate therewith, a pin projecting therefrom, a signal circuit, a circuit closer in said signal circuit in the path of said pin, 80 and a signal adapted to be actuated when the circuit is closed by said pin contacting with said circuit closer. 85

In testimony whereof, we affix our signatures in presence of two witnesses.
